UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, OF SAME PLACE.

DESIGN FOR A RUG.

SPECIFICATION forming part of Design No. 28,164, dated January 11, 1898.

Application filed December 9, 1897. Serial No. 661,321. Term of patent 3½ years.

To all whom it may concern:

Be it known that I, ADOLPH PETZOLD, a citizen of the United States, residing in the city of Philadelphia, State of Pennsylvania, have invented and produced a certain new and original Design for a Rug, of which the following is a full, clear, and exact description, reference being had to the accompanying drawing, forming a part of this specification.

10 My invention relates to the surface ornamentation of woven rugs and is shown in the accompanying drawing as applied to a Smyrna rug.

15 It consists of a rectangular outline or border of scroll-like figures, with floral figures in the field center on each side of a central figure, which is in the form of a shield in general outline, surmounted by an eagle, the center of the shield containing a cross and crown and other emblematic figures, as shown. 20

I claim as new and of my invention—

The design for a rug substantially as shown and described.

In testimony whereof I have hereunto affixed my signature this 28th day of October, 25 A. D. 1897.

ADOLPH PETZOLD.
